UNITED STATES PATENT OFFICE.

HENRY M. BISSELL, OF PITTSBURG, PENNSYLVANIA, ASSIGNOR TO BISSELL & CO., OF SAME PLACE.

GAS-STOVE.

SPECIFICATION forming part of Letters Patent No. 426,101, dated April 22, 1890.

Application filed December 23, 1889. Serial No. 334,605. (No model.)

To all whom it may concern:

Be it known that I, HENRY M. BISSELL, a citizen of the United States, residing at Pittsburgh, in the county of Allegheny and State of Pennsylvania, have invented or discovered certain new and useful Improvements in Gas-Stoves, of which improvements the following is a specification.

The invention described herein relates to 10 certain improvements in gas-stoves for fire-places. As heretofore constructed and arranged it has been necessary to remove the grate or coal-basket before the gas-stove could be put in place and connected to the 15 gas-supply pipes, thereby causing considerable labor and delay in changing from one kind of fuel to the other.

The object of the invention is to provide a stove that can be readily put in place for use 20 without disturbing the coal-burning arrangements in the fire-place, and can be easily removed when it is desired or necessary to use coal.

In general terms, the invention consists in 25 the construction and arrangement of mechanical devices or elements, all as more fully hereinafter described and claimed.

In the accompanying drawings, forming a part of this specification, Figure 1 is a front 30 elevation of my improved stove as applied to a fire-place. Fig. 2 is a rear elevation of the stove removed from the fire-place; and Fig. 3 is a sectional view, the plane of section being indicated by the line $\alpha\alpha$, Fig. 2.

35 In the practice of my invention a plate 1, corresponding to the ordinary summer-front, is placed in the fire-place, which is of the usual or ordinary construction, and can therefore have the plate applied without disturbing 40 the grate or coal-basket, as shown in Fig. 3. Onto this plate 1 is attached a frame 2, forming the top, sides, and the front of the upper portion of the gas-stove. This frame is preferably connected to the plate by screws 45 or bolts, but may be formed integral therewith, if desired. The bottom of the fire-chamber is formed by a shelf 3, extending

across the stove and secured at its ends to the sides of the frame, and on this shelf is supported the back plate 4 of the stove, arranged a short distance from the plate 1, and extending from side to side of the stove and up to the top thereof, as shown in Fig. 3. This back plate is provided with a nozzle or pipe-section 5, extending rearwardly through 55 the plate 1 into the fire-place, and serving as the escape for the products of combustion. The burner or burners 6 are attached to or otherwise supported by the shelf 3, which also serves to support the fire-brick tile 8, 60 forming the back wall of the stove. The front of the lower portion of the stove is formed by a plate 9, removable so as to permit access to the burner and supply-pipe for the purpose of connecting and disconnecting 65 the same. The plate 9 is formed with openings for the admission of air, which flows thence up between the plate 1 and back plate 4, and being heated escapes through 70 openings in the top of the stove, as shown in Fig. 3.

Fire-places vary considerably in lateral and vertical dimensions, so that it is necessary to provide plates 1 corresponding in dimension to the standard sizes of fire-places, and then 75 for small differences reduce the plate by cutting or grinding. In order to avoid carrying such a large stock of plates and the cutting and grinding heretofore necessary, the plate 1 is provided with wings 10, adjustably attached thereto by bolts or rivets passing through slots in the wings, as shown in Fig. 2, so that the dimensions of the plate may be 80 changed to suit a large range of fire-places.

The stove is provided with a removable 85 front plate 11, adapted, where no fire is required, to close the front of the stove, the whole structure presenting the appearance of a summer-front for the fire-place.

I claim herein as my invention.

1. The combination of a plate or summer-front constructed to close the front of a fire-place lying in or approximately in the plane of the front of the fire-place, and a gas-stove

attached to said plate or summer-front, substantially as set forth.

2. The combination of a plate or summer-front lying in or approximately in the plane of the front of the fire-place, provided with adjustable wings, whereby said plate may be made to fit in and close the fronts of fire-places of different dimensions, and a gas-stove

attached to said plate or summer-front, substantially as set forth.

In testimony whereof I have hereunto set my hand.

HENRY M. BISSELL.
